Primary Examiner — Michael A. Pratt

(57) **CLAIM**

The ornamental design for a response switch for audiometer, as shown and described.

DESCRIPTION

1. Response switch for audiometer

1.1 : Perspective

1.2 : Perspective

1.3 : Front

1.4 : Back

1.5 : Top

1.6 : Bottom

1.7 : Left

1.8 : Right

1.9 : Cross sectional

The product is for audiological tests; when the examinee hears the test sound, the examinee pushes down the center button shown in the front view of the subject design to inform the examiner that the sound is heard; fig. 1.9 is a cross-sectional view taken along A-A' line shown in fig. 1.3.
